CLAIM

The ornamental design for a shoe stretcher, as shown and described.

DESCRIPTION

FIG. 1 is a front, top, left side perspective view of a shoe stretcher showing my new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof, the left side being a mirror image of FIG. 6.

The broken lines shown are included for the purpose of illustrating the unclaimed portions of the article and form no part of the claim.
